UNITED STATES PATENT OFFICE.

THOMAS MIDGLEY, OF WORTHINGTON, OHIO, ASSIGNOR TO MORGAN & WRIGHT, OF DETROIT, MICHIGAN, A CORPORATION OF MICHIGAN.

CONTINUOUS CALIPER FOR RUBBER-TREATED FABRIC.

1,184,002.

Specification of Letters Patent. Patented May 23, 1916.

Application filed March 26, 1914. Serial No. 827,328.

To all whom it may concern:

Be it known that I, THOMAS MIDGLEY, a citizen of the United States, residing at Worthington, county of Franklin, and State of Ohio, have invented certain new and useful Improvements in Continuous Calipers for Rubber-Treated Fabrics, of which the following is a full, clear, and exact description.

10 This invention relates to the manufacture of rubber treated fabrics, and has for an object to provide apparatus for indicating variations in the thickness of a web of rubber treated fabric traveling from the rubber 15 treating calender rolls to the take-up stock roll.

In treating fabric with rubber it is customary to pass the fabric in the form of a ribbon or web between calender rolls one of 20 which is supplied with a film of rubber from a suitable source and applies this film to the web during its passage between the rolls. The web so treated is then spooled upon a 25 stock roll with a backing of fabric separating and keeping the convolutions from adhering together.

My invention provides an apparatus for slightly tensioning this web between calender rolls and stock roll and indicating the 30 thickness of the tensioned web.

In the drawings one embodiment of my invention is shown, in which drawings—

Figure 1 is a side elevation of the apparatus; Fig. 2 is a front elevation of the gage 35 mechanism; Fig. 3 is a sectional view on the line 3—3, Fig. 2.

Referring to the drawings, 10 and 11 40 designate calender rolls of the usual and well known type employed in treating a fabric web 12 with rubber. The web passes from the calender rolls over a guide roll 13 carried on a suitable frame 14 and is then spooled upon a stock roll 15 carried by the frame and preferably power driven as indicated at 16. A backing 17 of fabric is applied to the rubber treated web from a supply roll 18 carried by the frame and separates the convolutions of the rubber treated fabric on the stock roll.

50 In carrying out my invention a pair of brackets 19 is bolted to the frame 14 and is connected at the free ends by a tie rod 20 which extends transversely below the path of the web 12. A pair of supporting plates 55 21 is secured to the outer ends of the tie rod

by split ring clamps 22. Each plate is equipped with a pair of parallel roller bearings 23, the bearings of both plates being in alinement and forming anti-friction supports for an idle roller 24. The roller is 60 formed with a peripheral groove 25 near each end which snugly receives the corresponding pair of bearings 23 and prevents endwise movement of the roller. The roller extends transversely underneath and supports the rubber treated web between the margins thereof and is so elevated by the bearings 23 that it deflects the web upwardly out of its normal path between the calender rolls and guide roll thus tensioning the web. Each end of the roller is uniformly 65 reduced as shown at 26 for a purpose which will presently appear.

Positioned at each end of the tension roller 24 is a carriage 27 which is mounted 70 between guides 28 on the related supporting plate to slide toward and away from the path of the web. An arcuate bracket arm 29 is swiveled on the carriage by a pin 30 and carries a sleeve 31 which supports the 75 margin of the web and which snugly receives the corresponding reduced end 26 of the roller, the surface of the sleeve and roller being flush with each other and presenting a continuous supporting surface for the web. The sleeve is revolvably secured to the arm by a pin 32 and both the sleeve and roller are rotated as a unit by friction of the web passing thereover whereby the 80 free and unobstructed travel of the web is assured. An ordinary indicator 33 is fixed to the tip of the arm, the indicator stem 34 carrying a roller 35 which rides on the web as it passes over the supporting roller 24 and transmits the variations in the thickness thereof to the indicator in the usual manner.

In operation by virtue of the web being tensioned by the roller 24 all creases, wrinkles, and other irregularities in the web are removed so that the reading of the indicator accurately indicates the true thickness of the web. Both indicators operate simultaneously through the instrumentality of the roller 35 upon opposite longitudinal edges of the web and indicate the respective thicknesses of said edges whereby any variation may be observed and the rubber treating mechanism then regulated to correct the same. Both carriages 105 110

27 may be withdrawn from the web until the sleeves 31 disengage from the roller 24 whereupon the bracket arms 29 may be swung out of the way when desired. When 5 again swung back into position, the sleeves engage with the corresponding ends of the roller and anchor the indicators in operative position with respect to the web.

It will be noted from the above description that the sleeve 31, or member which supports the margin of the web, is movable as a unit with the indicator, toward and away from the path of the web over the member. The object of this construction is 15 that the member 31 will, by movement as a unit with the indicator, be always maintained in fixed position relatively to the indicator so that accurate readings will be possible even while the unit is being moved bodily upon the rubber treated web to 20 various positions.

Having thus described my invention, what I claim and desire to have protected by Letters Patent is:

25 1. A caliper including a roller for supporting a traveling web, a support, an arm slidably mounted thereon movable toward and away from the path of the web over the roller, a sleeve carried by the arm for receiving one end of the roller and anchoring 30 said arm, and an indicator carried by the arm co-acting with said sleeve for engaging and indicating the thickness of the web.

2. A caliper including a support, an idle roller thereon for supporting a traveling 35 web, one end of the roller being uniformly reduced, a carriage slidably fitted on said support for transverse movement toward and away from the path of the web, a bracket arm swiveled on said carriage, a 40 sleeve carried by said arm for receiving said reduced end of the roller, and an indicator carried by said arm for co-acting with said sleeve in engaging and indicating the thickness of the web.

45 3. A caliper embodying a support, a roller thereon for supporting a traveling web and having peripheral grooves, roller bearings on the support fitting in corresponding peripheral grooves in the roller and preventing endwise movement of the roller upon the support, an arm slidably mounted on the support at one end of the roller and movable toward and away from the path 50 of the web over the roller, a sleeve carried 55 by the arm for engaging the end of the roller and anchoring the arm, and an indicator carried by the arm and coacting with the sleeve for engaging and indicating the thickness of the web.

Signed at Detroit, county of Wayne, State of Michigan, this 23rd day of March, 1914.

THOMAS MIDGLEY.
